R. W. CARPENTER, OF CHICAGO, ILLINOIS.

Letters Patent No. 76,159, dated March 31, 1868.

COUPLERS FOR ORGANS, &c.

The Schedule referred to in these Letters Patent and making part of the same.

TO ALL WHOM IT MAY CONCERN:

Be it known that I, R. W. CARPENTER, of Chicago, in the county of Cook, and State of Illinois, have invented a new and useful Improvement in Couplers for Reed and Pipe Musical Instruments; and I do hereby declare the following to be a full, clear, and exact description of the same, reference being had to the accompanying drawings.

My invention relates to an improved form of coupler for reed and pipe organs, by which a great economy of room in the instrument and facility of construction are effected; and it consists in making the coupler of a single rod acting as a simple lever; and second, in the peculiar form to which said rod is bent so as to secure perfect action without interference with each other. It may be attached to organs or melodeons having a single bank of keys, and like ordinary couplers it opens the note an octave above the one fingered.

In order that others may understand the construction and operation of my coupler, I will proceed to particularly describe it.

A, fig. 1, represents the reed-board of the instrument, having one, two, or more sets of reeds operated by a single valve, V, and tracker-pin, b, in contact with the under side of the key B. These several parts being similarly made to like parts in other instruments, need no description. The coupler C is made of one piece of stout wire, bent in such shape as shown in Figure 2, having one end, at a, hammered thin, and a hole through it, in which the tracker-pin b is put when the several parts are in their proper position. It is made by being bent, (beginning with the end a, having the hole in it, and keeping the thin portion horizontal,) at about four inches from the end upward, then at about one-half inch from the first angle, bending to the left, and continuing for about six inches, then upward, as before, for about one-half inch, then backward, parallel to the first part, about four and one-half inches, then directly downward for an inch and a half, to the end, c, the two end portions, m and n lying in horizontal planes about one inch apart. This shape admits of their being placed very close together, and allows of sufficient motion to open the valves without coming in contact at any point with each other. The coupler C is attached to the instrument between the key and reed-boards at the angle x, a place being cut into the wood to admit each wire, and it is secured by a small strip of wood placed above, which is fastened down by screws. The opening is sufficiently large to allow of some motion to the coupler, and is lined with flannel, in the usual manner, to prevent any noise. The end, c, rests loosely in a slot formed by placing a strip of wood to the back of the coupler-bearing, at such distance as will allow the wire to enter freely, and in which it is free to move up and down when acted upon by the coupling-lever D. When placed in this position, they lie one just under each of the keys B, but at such distance that they will not be acted on by the said key when not in use, and extend over the space of thirteen keys, so that, when desired, any key may be connected or coupled with that key which is an octave above. On the under side of each key, at a proper place to act upon the coupler C, is secured a piece of wood, I, with a head or bolster, as shown in fig. 2, and when the end, c, of the coupler is raised up by the lever D, the two are brought in contact, so that as the key B is pressed downward, it opens its proper valve by the tracker-pin b, and, by the coupler, the valve of that key an octave above. The coupler is connected with the tracker-pin of this octave by the collar or ring d, of wood or leather, which is glued to the tracker-pin at the proper place, and on which the end, a, of the coupler presses when acted on by its proper key, the tracker-pin being passed upwards through the hole in the end, a, as shown in figures. A small screw is placed in the key B under the head of the piece I, by means of which said piece may be adjusted by turning the screw out or in, as may be necessary, when the head of the piece I may have been worn by use. The lever D passes under the couplers, and is hinged to the upper side of the coupler-bearing, and can be turned up or down, at the pleasure of the performer, by means of a stop in the usual manner. As it is turned up it raises all the couplers from the seat F, so that they just touch the keys above them at the points ee, and no matter how slightly any of the keys be depressed, the motion is instantly imparted to the key an octave above, while from the shape of the coupler, and manner of connection, no key below can be affected, as, should the coupler be depressed by any key at the end, a, although the part m would fall with it, yet the key in connection with it would not be affected, as it rests upon its tracker-pin, which is kept in its place by the valve-spring s.

It is evident that the particular shape and form in which the coupler-rod is bent, and the particular mode of applying it may be varied, without changing the character of the invention; and I therefore claim as new—

A simple lever-coupling formed from a single rod bent and applied substantially in the manner shown and described.

R. W. CARPENTER.
